UNITED STATES PATENT OFFICE.

FRANK CLEWLEY, OF PHILADELPHIA, PENNSYLVANIA, ASSIGNOR TO SIMON FRIEDBERGER, OF PHILADELPHIA, PENNSYLVANIA.

KNITTED FABRIC.

1,139,343.

Specification of Letters Patent. Patented May 11, 1915.

Application filed August 24, 1914. Serial No. 858,238.

To all whom it may concern:

Be it known that I, FRANK CLEWLEY, a citizen of the United States, residing at Philadelphia, county of Philadelphia, and State of Pennsylvania, have invented a new and useful Improvement in Knitted Fabric, of which the following is a full, clear, and exact description, reference being had to the accompanying drawings, which form a part 10 of this specification.

The object of my invention is to provide a new and improved fabric especially adapted for towels, wash cloths and other similar goods which are frequently soiled and wetted and which it is important, from a sanitary standpoint, should be such open mesh as to be capable of being quickly and thoroughly dried. In a patent issued to me February 16th, 1904, No. 752,033, a fabric of 15 this character is set forth in which chains of knitted loops, each chain composed of a single weft thread, are united by warp or filling threads alternately deflected to the right and left. This fabric meets all sanitary requirements but when applied to certain goods it does not possess the strength in 20 the line of the weft that it is desirable for it to have.

The object of the present invention is to 25 provide a knitted fabric possessing a maximum of strength on the line of the weft.

The invention consists of a fabric having 30 chains of knitted loops, and filling threads alternately deflected to the right and left, as in said patent, but in which each chain 35 of loops is formed by means of two separate weft threads forming alternate loops of the chain, and consists also of a fabric wherein the filling threads are interlaced with the 40 weft threads in a particular manner that will be clearly apparent from the following description in connection with the accompanying drawings, which illustrate a preferred embodiment of my invention and in 45 which—

Figure 1 is an enlarged face view, and Fig. 2 a face view on a smaller scale, of a fabric embodying my invention.

The fabric is formed of two series of weft 50 threads *a* and *b* and two series of warp or filling threads *c* *d* and *e*. Each weft thread of one series is interlaced with a weft thread of the other series to form loops comprising one of the series of chains *v*, *w*, *x*, *y*, *z*, *u*, etc.

55 The general direction of the filling threads *c*,

d and *e* is the same as that of the weft threads, but they are alternately deflected to the right or the left either between adjacent chains or across two or more adjacent spaces between chains; each of said filling threads 60 extending, in its passage through each loop, between two weft threads *a* and *b* of a pair.

Starting with either weft thread of any one of the chains (say the weft thread *a* at the second loop from the top of chain *x*), 65 it will be observed that it extends down and through the third loop, formed by thread *b*; thence up and through the first loop, formed by thread *b*; thence down to complete the second loop and again through the third 70 loop, and continues down through the fifth loop, formed by thread *b*; thence up and again through the third loop; thence down to complete the fourth loop: and so on. Starting with the weft thread *b* at the third 75 loop of the same chain *x*, it extends down and through the fourth loop, formed by thread *a*; thence up and through the second loop, formed by thread *a*; thence down to complete the third loop and again through 80 the fourth loop, and continues down through the sixth loop, formed by thread *a*; thence up and again through the fourth loop; thence down to complete the fifth loop: and so on. Thus each weft thread extends alternately up the length of one loop and down the length of three loops and in its passage 85 up and down extends thrice through each loop formed by the other weft thread.

Each filling thread extends, in its passage 90 through a loop, back of two sections of one weft thread and in front of one section of the same weft thread and one section of the other weft thread. If the filling thread, in its extension in one direction across the fabric, after passing through one loop, does not extend beyond the corresponding given chain, it is deflected, in the opposite direction, through the loop below it and thence across to the next chain and through the 95 loop thereof corresponding to the last named loop of the first chain. If the filling thread, in its extension across the fabric, passes across a plurality of successive spaces, it extends successively through corresponding 100 loops of successive chains, and in its return in the opposite direction, is deflected first through the next lower loop of the last chain.

Thus starting with the filling thread *c* 110

to the left of the first loop of chain *x*, it will be observed that it extends to the right through the first loop of chain *x* and the first loop of chain *y*; thence to the left 5 through the second loop of chain *y* and the second loop of chain *x*; thence to the right through the third loop of chain *x* and the third loop of chain *y*; thence to the left through the fourth loop of chain *y* and the 10 corresponding loops of chains *x*, *w* and *v*; thence to the right through the fifth loops of chains *v*, *w*, *x* and *y*; thence to the left through the sixth loops of chains *y*, *x*, *w* and *v*; and thence back and forth through 15 corresponding loops of chains *v* and *w* as above described.

In the particular fabric shown in the drawings, the chains are divided into sets of four, while the filling threads are divided 20 into sets of three (*c*, *d* and *e*). In those sections of the fabric in which each filling thread extends across only a single space between chains, two adjacent sets of chains are unconnected, forming an open space. Thus 25 an open space is formed between chain *x* of one set of chains and chain *w* of an adjacent set of chains. In those sections of the fabric in which a filling thread is carried across a plurality of spaces between chains, 30 two of the three threads are carried across the space between adjacent sets of chains, thus closing the space between the sets of chains.

The method of operating the needles 35 whereby the above fabric will be formed will be apparent to one skilled in the art, and as such operation forms no part of the invention, the same is not described.

While I have differentiated the weft 40 threads *a* from the weft threads *b* by section-lining the one and not the other, it will be understood that this is done merely to assist the eye in distinguishing the two threads in the drawings, it being understood 45 that these threads are similar one to the other and interlace with each other and with the filling threads in precisely the same way. Also the two filling threads *c*, *d* and *e* are of like character and are 50 given different reference letters because, in the fabric shown, three of such threads are employed in each set of chains to form a closed block separating two open spaces.

It will be understood that the number of 55 chains and the number of filling threads in each closed block and the number of chains spanned by the filling threads may be varied without departing from the invention.

While I have called the longitudinally 60 extending looped threads weft threads and the uniting cross threads warp or filling threads, they may be not improperly otherwise designated, as, for example, the looped thread may be termed warp threads and the other threads weft threads.

Having now fully described my invention, what I claim and desire to protect by Letters Patent is:

1. A knitted fabric comprising a weft formed of a number of pairs of threads 70 forming chains, each pair of threads extending along only a single chain and each thread of a pair forming loops interlaced with the loops of the other thread, and a warp formed of filling threads extending 75 back and forth between and interlaced with the chains.

2. A knitted fabric comprising a weft formed of a number of pairs of threads 80 forming chains, each pair of threads extending along only a single chain and the two threads of each pair forming alternate filling threads extending back and forth between and interlaced with the chains.

3. A knitted fabric comprising a weft 85 formed of a number of pairs of threads forming chains, each pair of threads extending along only a single chain, each thread of a pair extending successively forward, backward and forward to form a loop 90 engaging loops of the other thread respectively in front and back of the first loop and thence extending successively forward, backward and forward to form a loop beyond and interlaced with said forward loop of the 95 second thread, and so on, whereby a chain is formed composed of alternating loops, and a warp formed of filling threads extending between and interlaced with the chains.

4. A knitted fabric comprising a weft 100 formed of a number of pairs of threads, the two threads of each pair forming alternate loops of a continuous chain of loops, each thread in the formation of a complete loop extending through one of the adjacent loops 105 formed by the other thread thence through the other adjacent loop formed by the last named thread, and thence through the first adjacent loop to the next loop formed by the first thread, and a warp formed of filling 110 threads extending back and forth between and interlaced with the chains.

5. A knitted fabric comprising a weft formed of a number of pairs of threads, each thread of a pair being interlaced with the 115 other thread of the pair to form a continuous chain of loops, and a warp formed of filling threads deflected back and forth between the chains and extending, at each point of interlace with a chain, between the 120 two weft threads of a pair.

6. A knitted fabric comprising a weft formed of a number of pairs of threads, the two threads of each pair forming alternate loops of a continuous chain of loops, and a warp formed of filling threads deflected 125 back and forth between the chains and extending, at each point of interlace with a chain, between the two weft threads of a pair.

7. A knitted fabric comprising a weft formed of a number of pairs of threads, the two threads of each pair forming alternate loops of a continuous chain of loops, each 5 thread in the formation of a complete loop extending through one of the adjacent loops formed by the other thread thence through the other adjacent loop formed by the last named thread, and thence through the first 10 adjacent loop to the next loop formed by the first thread, and a warp formed of filling threads deflected back and forth between the chains and extending, at each point of interlace with a chain, behind two sections 15 of one weft thread of a pair and in front of another section of the same weft thread and a section of the other weft thread.

8. A knitted fabric comprising a weft formed of a number of pairs of threads, the 20 two threads of each pair forming alternate loops of a continuous chain of loops, and a warp formed of filling threads, each of which extends first in one direction through corresponding loops of a plurality of chains 25 and then in the other direction through the next adjacent set of corresponding loops of a plurality of chains, such filling thread in its passage through each loop, extending between the two weft threads of a pair.

9. A knitted fabric comprising a weft 30 formed of a number of pairs of threads, the two threads of each pair forming alternate loops of a continuous chain of loops, each thread in the formation of a complete loop extending through one of the adjacent loops 35 formed by the other thread thence through the other adjacent loop formed by the last named thread, and thence through the first adjacent loop to the next loop formed by the first thread, and a warp formed of filling 40 threads each of which extends first in one direction through corresponding loops of a plurality of chains and then in the other direction through the next adjacent set of 45 corresponding loops of a plurality of chains, such filling thread, in its passage through each loop, extending behind two sections of one weft thread of a pair and in front of another section of the same weft thread and a section of the other weft thread.

In testimony of which invention, I have hereunto set my hand, at Philadelphia, on this 21st day of August, 1914.

FRANK CLEWLEY.

Correction in Letters Patent No. 1,139,343.

It is hereby certified that in Letters Patent No. 1,139,343, granted May 11, 1915, upon the application of Frank Clewley, of Philadelphia, Pennsylvania, for an improvement in "Knitted Fabric," an error appears in the printed specification requiring correction as follows: Page 2, line 82, after the word "alternate" insert the words *loops of the chain, and a warp formed of*; and that the said Letters Patent should be read with this correction therein that the same may conform to the record of the case in the Patent Office.

Signed and sealed this 15th day of June, A. D., 1915.

[SEAL.]

J. T. NEWTON,

Acting Commissioner of Patents.
